(57) **CLAIM**

The ornamental design for a shoe, as shown and described.

DESCRIPTION

The present application is related to co-pending design application Ser. No. 29/679,354, filed on Feb. 5, 2019, and is related to co-pending design application Ser. No. 29/679,378, filed on Feb. 5, 2019, both of which are entitled "Shoe" and are incorporated by reference herein in their entirety. FIG. 1 is a top, left, and front perspective view of an ornamental design for a shoe;

FIG. 2 is a front elevational view of the shoe of FIG. 1; FIG. 3 is a rear elevational view of the shoe of FIG. 1; FIG. 4 is a left side elevational view of the shoe of FIG. 1; FIG. 5 is a right side elevational view of the shoe of FIG. 1; FIG. 6 is a top plan view of the shoe of FIG. 1; FIG. 7 is a bottom plan view of the shoe of FIG. 1; and, FIG. 8 is a magnified view of the area indicated in FIG. 6. The dash-dash-dash lines are included for the purpose of illustrating portions of the shoe that form no part of the claimed design. The dash-dot-dash broken lines depict boundary lines and form no part of the claimed design.
